UNITED STATES PATENT OFFICE.

FERNAND BOYER, OF PARIS, FRANCE.

METHOD FOR MANUFACTURING KNOTTED CARPETS.

1,180,003.

Specification of Letters Patent. Patented Apr. 18, 1916.

Original application filed September 30, 1914, Serial No. 864,221. Divided and this application filed August 5, 1915. Serial No. 43,775.

To all whom it may concern:

Be it known that I, FERNAND BOYER, manufacturer, a citizen of the République of France, residing at Paris, in the Republic of France, have invented certain new and useful Improvements in Methods for Manufacturing Knotted Carpets, of which the following is a specification.

This invention relates to a method for manufacturing knotted carpets and this application is a division of my co-pending application, Serial No. 864,221, filed September 30, 1914, for a machine for manufacturing knotted carpets.

As is known knotted carpets are made with pile threads slung around and tightened upon some of the warp threads of a tissue. According to the kind of knots employed these carpets are called either Smyrna or Persian carpets. These two knots do not differ much from each other, but the Smyrna knot is the more solid one. Such pile threads knotted into a tissue after the one or the other kind will project with their ends on one side of the tissue forming a velvet-like covering.

So far as I am aware all efforts hitherto made in producing such carpets by machinery have been unsuccessful, because the methods employed required very expensive, complicated and slowly working machinery which could not compete with skilful hand labor.

In a certain method the pile threads are first prepared separately being cut to size in a hand-operated apparatus and are then fed to the machine for knotting. This process limits the output and requires much attendance. In another method the tools employed are so clumsy that they are to be used only in coarse work. In fine work it was necessary to go over each series of pile knots several times, shifting the machinery each time, thereby reducing the output to such an extent as to make it impossible to compete with hand labor.

According to the present invention the knots are made in single rows even in fine work simultaneously on the whole width of the carpet and the pile threads are fed from a rack of spools containing as many spools as there are pairs of warps. The tissue of the carpet is formed during or rather between the introduction of the knots inasmuch as after each row of knots

a thread of the weft is woven in by any suitable weaving device.

The new method consists therefore in presenting the pile threads without cutting them previously at the proper length and one for a pair of warps in front of these by means of thread guides, then clamping the free ends, then stretching each thread in front of a pair of warps at an angle over thread rests, then engaging the threads by means of open tools located behind and reaching across the warp, then cutting the threads, then drawing both ends of each thread across the warps and around the same, then crossing the ends behind the warps, then forming a knot by drawing the crossed ends with open tools located in front of the warps across the same, the frictional contact with the same preventing the ends of the pile thread from slipping out of said open tools, then tightening the knot and pressing the newly formed knot against the finished portion of the carpet and then weaving in a weft thread.

In the accompanying drawings the method has been illustrated for the Smyrna and for the Persian knot.

Figures 1 and 2 and 4 to 8 are side elevations, representing different stages of the method, Figs. 3 and 16 are front views and Figs. 9 to 15 and Fig. 17 plans of the same all for the Smyrna knot.

As shown in Fig. 1 the ends of the pile threads *p* projecting downwardly from suitable thread guides 62 are clamped fast by clamp bars 96, 97 and presented in front of the warps 138, one pile thread for a pair of warps. The thread guides moving then upward close above the thread rests 125 fixed on bars 109 which have advanced in the meantime between the pile threads as is represented in Fig. 2 will then move horizontally sidewise stretching the pile threads at an angle over the thread rests as shown in Fig. 3. While the threads are thus being stretched horizontally over the said rests 125 open hooks 16 guided within guides 15 will advance from behind and across the warps and will with one hook between every two pairs of warps engage the pile threads whereupon the thread guides 62 will move vertically upward and assume the position represented in Fig. 3. Then the knives 120 fitted to a bar 120^a advancing and retreating again will thereby cut the pile threads,

as shown in Fig. 2, while the clamps 96, 97 will let go the clamped ends. The open hooks 16 now retiring will draw the ends of the pile threads across the warps and when 5 arrived behind the warps will retreat within their guides and clutch fastly the ends of pile threads each hook clutching two ends one end appertaining to the neighboring knot. This is shown in Figs. 4 and 9. 10 While the open hooks are drawing the thread ends across the warp the frictional contact with the same will prevent these ends from slipping out of the hooks. Then by a downward movement of the hooks 15, 15 16 the threads are carried downward along the warp to a position opposite the hooks 50 as shown in Fig. 5. Hooks 50 in front of the warp are so placed that when advancing each enters the space between the two 20 warp threads that have been wound around by one-pile thread. Hooks 50 now move out of their guides 49 at first only so far that their points enter between the warp threads in order to prevent their spreading. Holding pins 126 now move up from the position 25 shown in Fig. 4 to that in Fig. 5, whereupon the hooks 15, 16 are moved so far horizontally sidewise in the direction of the arrow in Fig. 10 that the clutched ends of the 30 pile thread are pulled laterally on one side of the two surrounded warp threads. Then hooks 50 are further advanced to the position of Fig. 5 and reach a position entirely on one side of the two pile thread ends as 35 shown in Fig. 10. Hooks 15, 16 will now descend a little, so that the ends of the pile thread which are not held by the holding pins 126 are caused to lie entirely within the hooks 50. Hooks 16 moving now horizontally 40 in the opposite direction to the position shown in Fig. 11 the ends of the pile threads which were not held by the holding pins are made to press laterally against the hooks 50. Hooks 15, 16 descend a little 45 farther and still more laterally from the position in Fig. 11 to that of Fig. 12 whereby the ends of the thread not held by the holding pin are made to press against the underside of hook 50 (Fig. 6). In this Fig. 50 6 however the end of the next following thread on this side has been omitted to make the illustration clearer. In this position the holding pins 126 are withdrawn again. Hooks 15, 16 now move farther sidewise and at the same time upwardly into the 55 position shown in Fig. 13 whereby the ends of the thread which had been held by the holding pins slide into the hooks 50 while

the other ends remain on the underside of the hooks. The thread has now been actually crossed above the hooks 50 as is represented in Fig. 14. The hooks 50 advance now a little farther (Fig. 7) and the hooks 15, 16 will at the same time move a trifle downwardly and the crossed ends caused to lie completely down into the hook 50. In this moment hooks 15, 16 will release the ends of the threads and the hooks 50 draw these ends downwardly through the warp and between the two warp threads along the other side of the warp where the two ends of each pile thread p will be held and clamped fast by the hook 50 which has now been drawn into its guide 49. By this operation the knotting of a Smyrna knot has 75 been accomplished (Fig. 15).

By a suitable instrument such as a descending reed 143, shown in Fig. 8, the knots are now pressed down against the finished part of the carpet while at the same time 80 hooks 50 are pulling on the thread ends. Thereby knots are made tight and brought to their proper places.

In Fig. 8, p^1 represents a tied knot and p^2 a knot being tied. After that the knots have been made a thread of weft is introduced to form the tissue of the carpet whereupon the whole process described may begin anew.

In Fig. 16 is shown in front view and in 90 Fig. 17 in a horizontal cross section a piece of a carpet manufactured by this process just described.

Having thus fully described and ascertained the nature of my invention and in 95 what manner it is to be performed, I declare that what I claim is:—

A method for manufacturing knotted carpets consisting in placing an uncut pile thread in front of a pair of warps, then 100 stretching the pile thread in front of its pair of warps, then cutting the pile thread and drawing the ends thereof across the warps and around the same, then crossing the ends of the pile thread behind the 105 warps, then forming a knot by drawing the crossed ends of the pile thread back between its pair of warps, then tightening the knot and pressing the thus formed knot against the finished portion of the carpet, and then 110 weaving in a weft thread.

In testimony whereof I have affixed my signature in presence of a witness.

FERNAND BOYER.
